UNITED STATES PATENT OFFICE.

JOSEPH MOSS, OF WOONSOCKET, RHODE ISLAND, ASSIGNOR TO WOONSOCKET MACHINE & PRESS CO., INC., OF WOONSOCKET, RHODE ISLAND, A CORPORATION OF RHODE ISLAND.

COTTON-PREPARING MACHINE AND THE LIKE.

Application filed May 13, 1922. Serial No. 560,738.

To all whom it may concern:

Be it known that I, JOSEPH Moss, a citizen of the United States, residing at Woonsocket, in the county of Providence, State 5 of Rhode Island, have invented a certain new and useful Improvement in Cotton-Preparing Machines and the like, of which the following is a specification, reference being had therein to the accompanying drawings.

The invention has relation more particularly to vertical or upright openers such as are employed in the preparation of cotton or other fibrous material for spinning, al- 15 though at least one of the features of the invention is applicable in the case of machines having horizontally disposed cylinders.

The invention consists in an improved 20 mode of mounting the cylinder of an opener upon its shaft; also, in an improved construction of the shell within which the said cylinder revolves; also, in the combination of stationary wings or baffle-plates with 25 the cylinder shell and external casing of a vertical opener to break up currents of air external to the said shell and within the said casing, and prevent circulation of air in currents between the shell and casing.

30 The invention is illustrated in the accompanying drawings, in which latter,—

Fig. 1 shows in vertical section an up- 35 right opener to which the features of the invention have been applied.

Figs. 1^a and 1^b are detail views on a larger scale of certain of the parts at the upper end and lower end, respectively, of the body of the composite or sectional cylinder.

Fig. 2 shows the said opener in horizontal 40 section in the plane indicated by the dotted line 2, 2, in Fig. 1.

Fig. 3 is a top view of the shell of Figs. 1 and 2.

Fig. 4 is an elevation of the said shell 45 with one of the wings or baffle-plates in section on line 4, 4, of Fig. 3.

Referring briefly to the main parts of the vertical opener, as the same are shown in the drawings,—

50 At 15, Figs. 1, 1^a, 1^b, and 2, is the shaft of the tapering or conical so-called cylinder; at 24, 24, Figs. 1 and 2, are the beater-blades of the said cylinder; at 22, Figs. 1, 2, 3, 4, is the perforated intermediate portion of the

tapering or conical shell within which the 55 said cylinder revolves, only a few perforations being represented in Fig. 4, and the perforations being omitted from other views for convenience; at 18, Fig. 1, is the bolster-bearing for the top portion of the 60 said shaft 15, and at 23 is the step-bearing for the bottom end of the said shaft; and at 27, Figs. 1 and 2, is the adjustment-lever supporting the said step-bearing, 29, Fig. 1, being a stirrup engaged with the outer end 65 of the said lever by means of a cross-pin 30, 28 an adjustment-screw with which the said stirrup is connected, and 32, Figs. 1 and 2, a hand-wheel by means of which the adjustment-screw is turned for the purpose of 70 moving the lever 27 to adjust the cylinder vertically to cause the outer ends of the beater-blades of the cylinder to occupy po- 75 sitions at the required distance from the inner surface of the shell. The cylinder 80 is shown as provided with driving means comprising a spiral gear 14, Fig. 1, mounted upon the upper end of the cylinder-shaft 15, and a driver spiral gear 19 mounted upon a transversely-extending power-driven jack- 85 shaft 6. At 17 is the external or main cas- 90 ing of the machine. The adjustment means and spiral gear drive for the cylinder are not claimed herein; they form the subject- matter of claims in application for U. S. 85 Letters Patent filed by me May 13, 1922, Serial No. 560,739.

Referring first to the mode of mounting the cylinder upon its shaft:—The construction of the body of the cylinder may vary 90 more or less. In this instance the said body is of built-up composite or sectional character, comprising in its make-up disk-shaped blade-carriers 241, and short cylinder-sections 242, termed separating pulleys, the said 95 blade-carriers and separating pulleys being mounted in an alternating succession upon the cylinder-shaft 15, and tied together in the direction of the length of the cylinder by means of one or more long tie-rods 243 100 passing through holes in the blade-carriers and pulleys and furnished with nuts 244 and washers upon their screw-threaded opposite ends. The cylinder-body is keyed to shaft 15 by means of a long key 245, Figs. 1, 1^a, 1^b, 105 and 2. The feature of invention in connection with the cylinder consists in providing, for the purpose of locating the cylinder-body

in proper position upon the shaft 15, collars 151, 152, Figs. 1, 1^a, 1^b, upon the cylinder-shaft 15 at top and bottom respectively of the cylinder-body. These collars are fixed 5 in place upon the shaft by means of tapering dowel-pins 153 occupying tapering holes made transversely through the collars and the shaft, the small ends of the said tapering dowel-pins projecting outward at one side of 10 the respective collars having burrs, 154, 154, which are struck up from the said small ends closely adjacent the peripheral portions of the respective collars, after the dowel-pins have been driven tightly into place. The 15 said burrs lock the dowel-pins against loosening and accidentally working out of place. In case it is desired to loosen one of the collars so as to leave the cylinder-body free to be slid lengthwise of the shaft, as in case removal of the cylinder-body from the shaft is 20 required, this may be accomplished by turning the burrs down close to the body of the tapering securing pin 153 of such collar, and driving the pin out of its holes in the collar 25 and shaft. This will render the collar free to be slipped lengthwise of the shaft, toward the adjacent end of the shaft and off from such end if required.

For the purpose of preventing any loose- 30 ness and play of the composite or sectional cylinder-body vertically relative to the shaft 15, I combine with the upper collar 151 one or more screws 155, the threaded stems of which occupy threaded holes tapped in the 35 under side of the said collar, and the heads of the said screws being arranged to make contact with the upper end of the cylinder-body. These screws are turned to cause their heads to bear firmly against the upper end 40 of the cylinder; and then the check nuts 156 with which the screws are provided are tightened up to lock the screws against accidentally turning so as to permit end-play of the cylinder-body upon the cylinder-shaft.

45 The described means of holding a beater cylinder in place upon its shaft is applicable in the case of other cylinders of preparing and the like machines, either vertical or horizontal.

50 Referring now to the improved construction of shell:—

The perforated conical shell 22 is made of three (more or less if preferred) segmental pieces of perforated sheet metal, Figs. 2, 3 and 4, which are held together by means of bolts 221, 221, that are engaged with the outwardly projecting flanges of angle-irons 222, 222, that are attached to the meeting portions of the segments, as by being electrically 60 welded to the exterior surfaces of such portions, or by being bolted or riveted thereto. The said bolts, when tightened up, serve to draw the angle-irons and the said meeting portions of the segments together. The 65 special feature in this connection is that the

joint between one segmental section of the shell and the next is an overlapping joint, such as that shown in Figs. 2 and 3, produced by offsetting the marginal portion of one segmental section so that such marginal portion will overlap the proximate marginal portion of the next adjoining section. The overlapping is at the inner surface of the shell, and is in the direction of rotation of the cylinder, so that fibers traveling around or revolving in unison with the cylinder are carried safely past the joint without danger of entering or lodging therein. The effect is to produce a practically smooth surface.

For the purpose of breaking up currents 80 of air outside the shell and within the external casing 17, and of preventing circulation of air in currents between the shell and casing, I provide baffle-plates or wings, such as those shown at 225, 225, Figs. 2, 3, and 4, 85 more or less radially disposed. These baffle-plates or wings preferably are attached to the exterior of the shell and project outward therefrom into close proximity to the external casing 17, although they may be attached 90 to the inner surface of the external casing 17 and project inwardly therefrom into close proximity to the exterior of the shell.

The outer portions of the baffle-plates or wings 225, 225, preferably are inclined forwardly in the direction of rotation of the cylinder. I find that when the baffle-plates or wings are thus inclined there is less tendency to eddying of the moving air around the outer edges of the baffle-plates or wings than 100 when they are simply radial.

What is claimed as the invention is,—

1. In a preparing machine, the combination with the cylinder-body, and a supporting and actuating shaft extending lengthwise through the cylinder-body, of collars upon the said shaft at the opposite ends of the cylinder-body serving to locate the cylinder-body in proper position upon the shaft, the shaft and said collars having tapering 105 holes therethrough, and tapering dowel-pins respectively occupying the holes in a collar and one of the holes in the shaft and locked in place therein.

2. In a preparing machine, the combination with the cylinder-body, and a supporting and actuating shaft extending lengthwise through the cylinder-body, of collars upon the shaft at opposite ends of the cylinder-body serving to locate the cylinder-body 120 in proper position upon the shaft, said collars and the shaft having tapering holes therethrough, and tapering dowel-pins, respectively occupying the holes in a collar and one of the holes in a shaft, and having burrs 125 struck up upon their projecting smaller ends which prevent the dowel-pins from working loose.

3. In a preparing machine, the combination with the cylinder-body, and a support- 130

ing and actuating shaft extending lengthwise through the cylinder-body, of fixed collars upon the shaft at opposite ends of the cylinder-body, and screws combined with 5 one of the said collars, taking bearing against one end of the cylinder-body, and locking the cylinder-body against movement lengthwise of the shaft.

4. In a preparing machine, the combination 10 with the cylinder thereof, of a shell surrounding the said cylinder, composed of a plurality of segments combined together by marginal portions thereof overlapping in the direction of rotation of the cylinder and 15 forming overlapping closed joints.

5. In a preparing machine, the combination 20 with the cylinder thereof, of a shell surrounding the said cylinder, composed of a plurality of segments combined together by means of angle irons attached to their marginal portions and bolts engaging with such angle irons, with overlapping closed joints formed by said marginal portions, overlapping in the direction of rotation of 25 the cylinder.

6. In a preparing machine, the combination 30 with the cylinder thereof, of a shell surrounding the said cylinder, composed of a plurality of segments combined together by marginal portions thereof overlapping at the inner surface of the shell in the direction of rotation of the cylinder and forming overlapping closed joints.

7. In a preparing machine, the combination 35 with the cylinder thereof, of a shell surrounding the said cylinder, composed of a plurality of segments combined together by

means of angle irons attached to their marginal portions and bolts engaging with such angle irons, with overlapping closed joints 40 formed by said marginal portions, overlapping at the inner surface of the shell in the direction of rotation of the cylinder.

8. In a vertical opener, the combination 45 with the cylinder-shell and a casing surrounding said shell, of baffle-plates or wings extending radially or substantially so across the space or interval between the said shell and casing for the purpose of breaking up 50 currents of air outside the shell and within the casing.

9. In a vertical opener, the combination 55 with the cylinder-shell and a casing surrounding said shell, of baffle-plates or wings extending radially or substantially so from the shell approximately to the casing for the purpose of breaking up currents of air outside the shell and within the casing.

10. In a vertical opener, the combination 60 with the cylinder-shell and a casing surrounding said shell, of baffle-plates or wings extending radially or substantially so from the shell approximately to the casing for the purpose of breaking up currents of air outside the shell and within the casing, the said 65 baffle-plates or wings inclining forwardly in the direction of rotation of the cylinder.

In testimony whereof I affix my signature in presence of two witnesses.

JOSEPH MOSS.
